(57) **CLAIM**

The ornamental design for a periphery of an outsole, as shown and described.

DESCRIPTION

FIG. 1 is a perspective view of a periphery of an outsole embodying my new design.

FIG. 2 is a left side view thereof;

FIG. 3 is a right side view thereof;

FIG. 4 is a top plan view thereof;

FIG. 5 is a bottom plan view thereof;

FIG. 6 is a rear elevation view thereof; and,

FIG. 7 is a front elevation view thereof.

Broken lines showing the remainder of the shoe in the figures are for illustrative purposes only and form no part of the claimed invention.

1 Claim, 6 Drawing Sheets*FIG. 1*

FIG. 2

FIG. 4

FIG. 5

FIG. 7

FIG. 6
